UNITED STATES PATENT OFFICE.

BERNARD D. WILLIS, OF OAK PARK, ILLINOIS, ASSIGNOR, BY MESNE ASSIGNMENTS, TO AUTOMATIC ELECTRIC INC., OF CHICAGO, ILLINOIS, A CORPORATION OF DELAWARE.

MULTIOFFICE TELEPHONE SYSTEM.

Application filed May 10, 1922. Serial No. 559,689.

This invention relates in general to multi-office telephone systems but more particularly to such systems as comprise in one network offices or exchanges of two different kinds, the offices of one kind being manual offices wherein connections are completed by operators, while the other kind of offices are automatic offices in which connections are completed by means of automatic switches, and the object of the invention is to provide new and improved circuit arrangements for handling inter-office calls between the automatic and manual exchanges.

Systems having both kinds of exchanges as above pointed out are becoming quite common and may arise either by consolidation of existing manual and automatic systems, serving the same territory, or by the process of changing over a manual system to an automatic system. Usually in the latter case only one office at a time is converted from manual to automatic and it follows that during the period of transition there will necessarily be both kinds of offices in operation. However the above situation may arise, it is necessary to provide suitable circuit arrangements for handling calls from the manual offices to the automatic offices, and from the automatic offices to the manual offices. The present invention is concerned only with the latter class of calls, and provides certain improvements in a system comprising automatic to manual trunks which are accessible to selector switches in the automatic offices and terminate in plugs in front of a B operator at the manual office, together with call registers for registering the digits in telephone numbers called by automatic subscribers when the trunks are taken for use, and an indicating device upon which such numbers are shown to the operator one after the other as fast as she can complete the desired connections.

The present invention may be considered to be an improvement on the system disclosed in Patent No. 1,539,925, issued June 2, 1925. The main feature of improvement may be said to consist in the provision of improved call register equipment, there being a group of relays provided to register each digit, which take the place of the step

by-step switches formerly used for this purpose. 55

Another feature is the provision of a pre-selecting line switch for preselecting idle call register sets, thus reducing to a minimum the time required to connect with an idle call register set after the cord has been seized, and in this way reducing the possibility of mutilating a call by the subscriber dialling the second digit before an idle call register has been seized. 60

A further feature consists in the provision of a two conductor trunk circuit between the manual and automatic exchange having associated therewith a common group busying conductor, which is common to a group of trunks and which makes the trunk group busy, either if the operator leaves her position, or if all call register sets of the group are in use. Various other detail improvements will be further pointed out in the detailed specification which follows. 65 70 75

In the drawings, comprising Figs. 1, 2, 3 and 4, there is shown by means of the usual circuit diagrams the apparatus and circuit connections thereof, which is involved in a complete connection extending from the automatic substation A, Fig. 1, to a manual substation A', Fig. 2. The apparatus indicated in Fig. 1 is located in an automatic exchange, while the apparatus indicated in Figs. 2, 3, and 4 is located in a manual exchange. Inasmuch as the automatic switching equipment itself and the manual equipment are both well-known and of the usual type, no detailed description of the mechanical features of this apparatus will be given, 80 except in so far as it is found convenient or necessary to do so in the explanation of the operation of the circuits. 85 90

Referring to Fig. 1, the substation A is one of a plurality of ordinary automatic substations terminating in the automatic exchange previously referred to, and is provided with the usual talking equipment and ringer, and also with a calling device of well known type which is indicated by the reference character S, through the medium of which the subscriber controls the central office switches. 95 100

The line conductors 11 and 12 extend to the exchange where they terminate in the line switch C, which may be briefly de- 105

scribed as a rotary line switch whose movable terminals or wipers have no normal position, and which have movement in a forward direction only. The construction of a line switch of this type is well known in the art, and its function, also well understood, is to extend its associated line when calling to an idle trunk line. In carrying out this object, a plurality of these individual line switches are given access to a group of trunk lines extending to first selector switches. One of the trunk lines to which the line switch C has access is shown in the drawing as extending to the first selector D, which is a vertical and rotary selector of the well known Strowger type. In a multi-office system of the kind herein contemplated the first selector switches are usually known as office selectors and the selector D in common with a plurality of similar selectors has access to a plurality of groups of trunk lines, each of which groups may extend to a different office or exchange in the system. Some of these groups of trunk lines may extend to automatic exchanges, while other groups may extend to manual exchanges. A trunk line in one of the latter groups is shown in the drawing, and comprises the repeater E and the trunk line conductors 130 and 131, which extend to the manual exchange in question and there terminate in the plug ending cord circuit O, Fig. 2. The cord circuit O is one of a plurality of similar cord circuits, at a B operator's position 35 in the manual exchange and constitutes the means whereby the trunk line shown may be connected by the operator with any one of the manual lines terminating in the manual exchange. One of these lines is the line of substation A', which with its associated line equipment is shown at the right of Fig. 2.

The repeater E is an automatic impulse repeater of the general type in common use, and in addition to repeating operating impulse to the distant manual exchange, provides holding circuits for the automatic switches, and thus renders it unnecessary to use more than two conductors for the inter-office trunk line.

From the foregoing it will be understood that the operation of an office selector, such as the selector D, in response to the calling of the first digit in the telephone number of a line in the manual exchange, will result in extending the connection from the line of the calling automatic subscriber to an idle plug ending cord circuit in the manual exchange. In order to take care of the remaining digits in the numbers there is provided for each B operator's position a plurality of register sets as hereinbefore stated, each set being capable of registering all the digits in a telephone number, with the exception, of course, of the first digit which controls the office selector in the automatic

exchange. In Figs. 3 and 4 I have shown one of these register sets complete. It comprises register control switch RCS, Fig. 3, and register relay groups R' and R², Fig. 4. The register control switch RCS, which may be described briefly, consists essentially of wiper 355 and its associated set of bank contacts, together with a stepping magnet 359 for advancing the switch wipers, and a release magnet 358 for restoring it to normal. A set of rotary off-normal springs 357 are included in the circuit of the latter magnet and are closed on the first movement of the switch.

The register sets comprise groups of relays, there being a group for each digit in the called number. The arrangement is such that the various digit lamps are connected up by the operation of one or more relays of a group. A switching relay of each group is also operated to prepare the next group, and so on. When a final digit has been set up the switching relay of the last group closes a circuit to cause a consecution control switch to select the register set which is in use after which a circuit is closed to light the call indicating lamps corresponding to the digit set up.

The indicating device by means of which called telephone numbers are shown to the operator is shown in connection with the register sets shown in Fig. 4. It comprises, essentially, a plurality of groups of switchboard lamps, there being one group of lamps for each register relay group in a register set. It will be understood that the lamps have the function of illuminating the digits of the called numbers and causing them to stand out so as to be readily distinguished. The digits are preferably marked in black on the reverse side of a white semi-transparent surface and ordinarily are not very conspicuous. But when the switchboard lamp immediately behind any character or figure is lighted such character or figure will stand out very clearly and is read with great facility. The lamps of the indicating device are wired to contacts on the relays of the register set shown, and are also wired to similar contacts on the relays of the other register sets at the position.

As stated hereinbefore, there are a plurality of register sets providing for the registration of a plurality of calls simultaneously or close together. These registered calls are displayed on the indicating device one after the other as fast as the operator can complete the connection by plugging into the multiple jacks which correspond to the members displayed. In order to switch the calls over onto the indicating device in succession a so-called consecution control switch is provided. This switch is shown in Fig. 2 where it is indicated by reference character CCS, and comprises a single wiper and bank of con-

5 contacts as shown in the drawing. The switch CGS is mechanically the same in construction as the rotary line switch C, Fig. 1, that is, its wipers have no normal position and moves in a forward direction only. The circuits, however, are changed and will be described hereinafter.

10 Each register set is provided with a time controlled switch which in the case of the register set shown in Figs. 3 and 4 is indicated by the reference character P, Fig. 3. The switch P may be similar in construction to the register control switch but is operated by timing mechanism instead of by means of 15 impulses corresponding to digits in the called telephone numbers. The time mechanism, which may be common to the exchange, is indicated by the reference character T, and may consist of any suitable kind 20 of clock-work controlled mechanism which is adapted to produce impulses at the rate of one per second.

In order to properly extend calls which are received at the manual exchange to the 25 register sets each cord circuit is provided with an individual plunger type line switch which is maintained positioned before an idle register set when not in use by a master-switch. These line switches have common 30 access to all the register sets. The reference character C', Fig. 3, indicates a plunger type line switch which is individual to the cord circuit O, Fig. 2, and which has access to the register set shown in the drawings, 35 assumed to be the first, and also to the other register sets which are provided at the B operator's position in which the cord circuit O terminates. Line switch C' and the master-switch MS, are of well known construction and function and on this account will not be described in detail as to their mechanical operation.

Having described in a general way the layout of the system herein disclosed, the 40 operation of the circuits will now be described more in detail, it being assumed for this purpose that the subscriber at substation A, Fig. 1, desires to obtain a connection with the manual subscriber at substation A', Fig. 2, whose telephone number, it will be assumed, is 345. When the receiver is removed at substation A, a circuit is completed over the line conductors 11 and 12 for the line relay 14 of the individual line switch 45 C. Upon energizing, the line relay completes at its armature 20 a circuit which extends through the switching relay 13 and the stepping magnet 15 in series to battery, and at its armature 19 connects the test 50 wiper 26 to the above circuit at a point midway between the switching relay and the said stepping magnet. The operation now depends upon whether the first selector 55 trunk with which the wipers of the line switch are in connection is busy or is not

busy. If this trunk line is busy the test contact 31 associated therewith will have a ground potential upon it, the switching relay 13 will be short circuited, and the stepping magnet 15, which interrupts its own 60 circuit, will operate as a buzzer to advance the wipers 25-27, inclusive, step by step in search of an idle trunk line. This operation will continue as long as the test wiper 26 continues to engage grounded or busy test 65 contacts. However, we may assume that in the present case when the call is initiated the selector D is idle, and the test contact 31 therefore is not grounded. Under these circumstances when the line relay 14 is energized the switching relay 13 is energized immediately afterwards, with the result that the line conductors 11 and 12 are disconnected from the winding of the line relay 14 and from ground, respectively, and are extended 70 by way of armature 16 and 18 and their working contacts, wipers 25 and 27, bank contacts 30 and 32, and armatures 60 and 62 and their resting contacts, to the upper 75 and lower windings of the line relay 50 of the selector D.

As soon as the line is extended to the selector D as above described, the line relay 50 will be energized and will close the circuit of the slow acting release relay 51. 80 Upon energizing, the latter relay prepares the circuits of the selector for operation in its vertical movement in the usual manner, and also completes a holding circuit extending back to the line switch C as follows: 85 ground, working contact of armature 63 and the said armature, conductor 64, bank contact 31, test wiper 26, armature 17 and its working contact, winding of the switching relay 13; and the winding of the stepping 90 magnet 15 to battery. It is understood that the above holding circuit is completed before the slow acting relay 14 has had time to de-energize. In addition to maintaining the switching relay energized, the holding circuit also serves to provide ground to the 95 multiples of test contact 31 and also to the multiple test contacts in which the private normal conductor 28 terminates in the banks of the connectors which have access to the line of substation A, thereby guarding the connection against intrusion in the customary manner.

The calling subscriber may now operate his calling device S in accordance with the 100 first digit of the desired number. Three interruptions are thereby produced in the circuit of the line relay 50, and the said relay is accordingly three times deenergized 105 momentarily, transmitting at each deenergization an impulse of current through the slow acting series relay 52 and the vertical magnet 56 to battery. By the operation of the vertical magnet the selector shaft is raised three steps, whereupon the wipers 110

70-72, inclusive, will be standing opposite the level of bank contacts in which are terminated the trunk lines extending to the manual exchange. The slow acting relay 52 is energized in series with the vertical magnet, retaining the armature attracted throughout the vertical movement of the switch, and upon the closure of the vertical off normal springs 59 completes a circuit for the stepping relay 53. Upon energizing, relay 53 prepares a circuit for the rotary magnet 54 at its lower armature and at its upper armature establishes a locking circuit for itself. At the end of the vertical movement of the switch the slow acting relay 52 is de-energized and closes the circuit of the rotary magnet, which is thereupon energized to advance the wipers 70-72, inclusive, into engagement with the first set of bank contacts in the level opposite which they are raised. The rotary magnet 54 also breaks the locking circuit of the stepping relay 53, which accordingly deenergizes and breaks the circuit of the rotary magnet, which thereupon deenergizes also and again closes its interrupter contact.

The operation now depends upon whether the trunk line with which the wipers have connected is busy or is not busy. If this trunk line is busy the test contact associated therewith will be grounded and the stepping relay 53 will be energized over a circuit which extends by way of the test wiper 71, armature 61 and its resting contact, interrupter contact of the rotary magnet, off normal springs 59, and the winding of the stepping relay 53 to battery. The stepping relay will therefore again close the circuit of the rotary magnet 54 which will operate to rotate the switch wipers into engagement with the next set of bank contacts. This operation in which the stepping relay and the rotary magnet are alternately energized and deenergized will continue as long as the test wiper 71 continues to engage grounded or busy test contacts. In the present case it will be assumed that the trunk shown in the drawings is the first idle trunk line, and when therefore the test wiper 71 arrives at test contact 74 and the rotary magnet is de-energized, the stepping relay 53 will not again be operated, but instead the switching relay 55, which heretofore has been short-circuited, will be energized by current flowing over the following path: grounded conductor 64, winding of the switching relay 55, interrupter contact of the rotary magnet 54, off normal springs 59, and the winding of the stepping relay 53 to battery. Owing to the high resistance of the switching relay 55, stepping relay 53 is not operated. Upon energizing, relay 55 disconnects the incoming line conductors from the windings of the line relay 50 and extends them by way of armatures 60 and 62 and

their working contacts, wipers 70 and 72, bank contacts 73 and 75, trunk conductors 76 and 78, and normally closed contacts of the reversing relay 100 to the upper and lower windings of the line relay 101 of the repeater E.

When the line is extended to the repeater, as above explained the line relay 101 is energized and closes a circuit of the slow acting release relay 102. Upon energizing, relay 102 completes a holding circuit extended back to the selector D and line switch C as follows: ground, armature 112 and its working contact, conductor 77, test contact 74, test wiper 71, and the armature 61 and its working contact to conductor 64, where, it joins the previously described holding circuit extending back to the line switch C. The above described circuit serves to maintain relays 55 and 13 energized throughout the duration of the connection.

In addition to closing the holding circuit for the automatic switches C and D, the relay 102 of the repeater E prepares a circuit at its armature 115 for the slow acting relay 103, closes a circuit at its armature 114 which energizes the polarizing winding of the electro-polarized relay 105, and at its armature 113 completes a bridge across the trunk conductors 130 and 131 which may be traced over the following path: conductor 130, armature 113 and its working contact, armature 116 and its resting contact, upper winding of the electro-polarized relay 105, normally closed contact springs controlled by armature 108 of relay 100, right hand winding of the impedance coil 106, and armature 111 and its working contact to the conductor 131. By the closure of this bridge across the trunk line a circuit is completed for the double wound line relay 204 in the cord circuit O, and the said relay 204 is therefore operated.

When the calling line is extended to the line relay 204 as above explained, the said line relay is operated, and completes an energizing circuit for the slow acting relay 203. Relay 203, on attracting its armature 215, closes one point in the circuit of relay 201, at its armature 217 closes an operating circuit for the individual line switch C' which extends as follows: ground, armature 217 and its working contact, armature 213 and its resting contact, conductor 234, resting contacts of spring 348 controlled by the armature 360 of switch C', winding of line relay 301 to battery. Line relay 301 energizes over this circuit and at its armature 349 completes a circuit for the pull down winding 302 of the line switch C', which may be traced as follows: ground, armature 349 and its working contact, winding 302, conductor 333, armature 310 and its resting contact to battery. The closure of the above traced circuit causes the plunger controlled by

110

115

120

125

130

armature 360 to be operated. The operation of the armature 360 opens the circuit of line relay 301 at springs 346 and 348 and at springs 347 and 348 completes a holding circuit to maintain the plunger in an operated position after the armature 349 of the line relay 301 restores. This circuit may be traced from ground, armature 217 and its working contact, armature 213 and its resting contact, conductor 234, springs 348 and 347, holding winding 303 of line switch C' to battery. The operation of the plunger caused the spring contacts 311, 313, 315, and 317 to engage springs 312, 314, 316, and 318, respectively.

The closure of springs 315 and 316 completes a circuit over the conductor 338 extending to the master-switch bank contact upon which the master-switch wiper 337 is now resting, for energizing the starting relay 336 of the master-switch MS. Upon energizing, the relay 336 closes a circuit for the locking magnet 335, which unlocks the master-switch shaft and thus brings about the realignment of all idle line switch plungers in front of the next idle call register set. The starting relay 336 also closes a circuit for the open main relay 334, which upon energizing, disconnects the common conductor 333 from the negative pole of battery, in order to prevent any of the line switches from being operated until the master-switch comes to rest.

The closure of contacts 317 and 318 prepares a circuit for lamp L⁴ in the cord circuit O, at contacts 311 and 312 a point in the impulsive circuit is closed, and at contacts 313 and 314 a circuit is closed for relay 306 in multiple with the holding winding 303 of line switch C'. The operation of relay 306 closes another point in the impulsive circuit at armature 341 and its working contact, and at armature 319 and its working contact a circuit is prepared over conductor 404 for the call register group switching relays 400 and 405, at armature 321 ground is removed from the bank contact of the time limit switch P, and at armature 320 a circuit is completed for the stepping magnet 324 of the switch P which may be traced as follows: ground, interrupter contacts 370, conductor 322, armature 323 and its resting contact, armature 320 and its working contact, stepping magnet 324 to battery. Switch P begins to operate to move its wipers 330 and 331 over their bank contacts, for a purpose which will hereinafter be described.

Everything is now in readiness for the transmission of the second series of impulses. The subscriber will now operate his calling device in accordance with the digit 4, which will cause the line relay 101 of the repeater E to fall back a corresponding number of times, which results in a like series of inter-

ruptions of the circuit in the line relay 204. Each time line relay 204 falls back an impulse is transmitted to stepping magnet 359 over the following circuit: ground, armature 218 of line relay 204 and its resting contact, conductor 233, contacts 311 and 312 of line switch C', armature 341 and its working contact, winding of relay 307, and the winding of stepping magnet 359 to battery. The first digit transmitted to the register 75 sets being the digit 4, the stepping magnet 359 receives 4 impulses which causes its wiper 355 to be set on its fourth pair of bank contacts. When the first impulse was transmitted over the impulsive circuit the slow relay 307 was energized. This relay remains energized during each series of impulses and at its armature 326 disconnects wiper 355 while the switch is rotating. At the termination of this series of impulses, the slow relay 307 deenergizes and at its armature 326 closes the following circuit: ground, resting contacts 328 controlled by armature 372 of relay 309, winding of relay 308, armature 326 and its resting contact, wiper 355, 90 bank contact 356, conductor 329, armature 407 and its resting contact, and the winding of relay 402 to battery. On completion of the above circuit relays 308 and 402 are energized in series.

The operation of relay 308 completes a circuit for relay 309, traced from ground, armature 354 and its working contact, winding of relay 309 and off normal springs 357 to battery. Relay 309 operates and at its armature 372 and its working contact completes a holding circuit for itself, at spring 328 and its back contact ground is removed from relay 308, and at springs 328 and 329 a circuit is completed for release magnet 358 105 to cause the wiper 355 to be restored to normal.

The relay 402, at its armature 403 and its working contact, closes a holding circuit for itself which may be traced as follows: 110 ground, armature 319 of relay 306 and its working contact, conductor 404, winding of relay 400, armature 403 and its working contact and the winding of relay 402 to battery. Relay 400 operates as soon as relay 309 pulls 115 up, being shunted out until this occurs, and at its armatures 407, 423, 415 and 416 switches the register control circuits to the next and in this particular case last register set, it being understood that any number of 120 register sets may be provided depending upon the number of digits in the called number.

The apparatus is now in readiness to receive the final series of impulses. The subscriber again operates his calling device, this time in accordance with the digit 5, which causes a similar operation of the line relay 101 of the repeater E, and line relay 204 of the cord circuit O. The stepping magnet 125 130

359 of the switch RCS is again operated over the previously traced circuit, this time causing the wiper 355 to step to the fifth contact set, after which the series relay 307 5 again falls back and this time closes operating circuits for relays 417 and 418 of the last register set. These circuits may be traced as follows: ground, spring 328 and its resting contact, winding of relay 308, and 10 armature 326 and its resting contact to wiper 355, where the circuit divides, one branch extending over bank contact 381, conductor 481, armature 415 and its working contact, conductor 483, armature 425 and its resting 15 contact, and the winding of relay 417 to battery, and the other branch extending over bank contact 380, conductor 480, armature 416 and its working contact, conductor 482, armature 484 and its resting contact, and the 20 winding of relay 418 to battery. Relay 417, on energizing, completes a holding circuit for itself which may be traced as follows: grounded conductor 404, winding of relay 405, working contact of armature 420 and 25 the said armature, and the winding of relay 417 to battery. A similar holding circuit for relay 418 is closed over conductor 404, winding of relay 405, working contact of armature 419 and said armature, and the winding 30 of relay 418 to battery. The release of the register control switch is brought about in the same manner as hereinbefore described by the operation of relay 309 and release magnet 358. Switching relay 405 operates 35 as soon as relay 309 pulls up, being shunted out until this occurs, and at its armature 413 completes a circuit for relay 305, from grounded conductor 404, by way of armature 413 and its working contact, conductor 414, 40 resting contact of springs controlled by armature 361 of relay 305, winding of said relay to battery.

On energizing, relay 305 locks itself at armature 361, stops the operation of the timing switch P, at armature 323, while at armature 363 the conductor 284 is connected to ground, thus closing a circuit through the lamp L', Fig. 2, and the relay 262 of the consecution control switch CCS. By the closure of this 45 circuit relay 262 is energized and lamp L' is lighted to notify the operator that a call has been registered on the associated register set. In addition to the foregoing, relay 305 disconnects conductor 271 from ground at armature 365 and extends it instead to the winding of relay 304. Conductor 271 may be considered as a test conductor and extends to the first contact in the bank of the consecution control switch CCS, since the register 50 set shown is assumed to be the first register set at the position. The other test conductors 272-276, inclusive, are of course associated with the other register sets at the same position.

65 Assuming that no other call is being

shown on the indicating device just at the present time the consecution control switch CCS is immediately operated to switch the registered call over onto the indicating device. The operation is as follows: When relay 262 energizes, it connects up the wiper 264 by means of armature 266, and at armature 265 closes a circuit for the slow acting line relay 261. Upon energizing, the latter relay closes a circuit at its armature 268 70 which includes the switching relay 260 and the stepping magnet 263 in series, and at its armature 267 connects the wiper 264 to the above circuit at a point midway between the said relay and magnet. The latter operation provides for advancing the wiper 264 in case the contact with which it is in engagement is grounded, but it will be assumed in the present case that the wiper is standing on the first contact of the bank 75 as shown in the drawing, and since the ground has been removed from this contact by the energization of relay 305, no rotation of the switch will take place. Instead, the switching relay 260, which is of high resistance is at once energized in series with the stepping magnet 263, the latter remaining inoperative, and breaks the circuit of the line relay at armature 269. The line relay is slow acting, however, and before it has time to fall back relay 304 in the register control switch is energized over the following circuit: from ground, by way of armature 268 and its working contact working contact of armature 270 and the said armature, working contact of armature 266 and said armature, wiper 264 and the bank contact engaged thereby, conductor 271, armature 365 and its working contact, and the winding of relay 304 to battery. Upon 80 energizing, relay 304 locks itself to the grounded conductor 404 at its armature 361. This operation connects conductors 404 and 271 together and a circuit is thus completed for supplying ground to the switching relay 260 in the consecution control switch CCS, in order to maintain this relay energized after the line relay 261 has deenergized. Relays 305 and 304 in the master control switch are now both energized, and the consecution control switch is in operated position (switching relay energized) with its wiper in engagement with the bank contact corresponding to the first register set. Other calls may be registered on the other 85 register sets at any time now and when registration is completed the lamps L², L³, etc., corresponding to the register sets in use will be lighted, but this has no effect on the consecution control switch CCS, which makes no further movement until the call on the first register set has been disposed of.

Relay 304 is the relay which switches over the registered call to the lamps of the indicating device and the manner in which this 90 120 125 130 135

as done will now be pointed out. When relay 402 operated it prepared at its armature 485 a circuit for indicator lamp 4 of the first digit extending from common conductor 490, armature 485 and its working contact, armatures 486 and its resting contact, armature 487 and its resting contact, armature 488 and its resting contact, conductor 421, lamp 4 to battery. When relay 417 and 418 were operated a circuit was prepared for lamp 5 of the last digit. This circuit extends from the common conductor 490, armature 412 and its resting contact, armature 428 and its resting contact, armature 426 and its working contact, armature 427 and its working contact, conductor 422, lamp 5 to battery. When armature 391 of relay 304 is attracted, ground is placed on conductor 490. It follows, therefore, that with the register relays in their present operated position conductors 421 and 422 will be grounded causing the indicating lamps No. 4 of the first group and No. 5 lamp of the last group to light to inform the operator that the called line number is 45.

The manner in which the operator handles the call thus displayed before her will now be considered. When relay 304 of the register control switch RCS pulls up and closes a circuit for displaying the registered number to the operator, it also closes at its armature 393 a circuit for the trunk or call signal lamp L⁴ in the cord circuit O, which may be traced as follows: from ground by way of the working contact of armature 393 and the said armature, spring bank contacts 318, and 317 of switch C', conductor 235, winding of relay 202 armature 211 and its resting contact, armature 222 and its resting contact, lamp L⁴ to battery. By the closure of the above circuit, lamp L⁴, which is individual to the cord circuit O, is lighted simultaneously with the call indicating lamps, thus enabling the operator to know which one of her cord circuits is being used by the automatic subscriber whose wanted number is at this particular time being shown on the indicating lamps. Having observed the number 45, and knowing by the lighting of the lamp L⁴ that the cord circuit O is the one in use, the operator will test the multiple jack of line number 45 with the tip of her plug in the usual manner, in order to find out whether or not the line is busy. If the line is found to be in use, the plug will be inserted in a "busy back" jack, of well known form and function, in order to give the calling subscriber a busy signal. Assuming, however, that the line found to be idle, the operator will at once insert the plug P in the jack of the wanted line, which in the present case is the jack J.

As soon as the plug is inserted in the jack a circuit is completed for the sleeve relay 209 in series with the cut off relay 240 of the called line, and the latter relay is energized to clear the line of its normal battery and ground connections in the usual manner. Relay 209 is energized also and at armature 227 disconnects the operator's head set. At the same time at armatures 227 and 229 the tip and ring conductors of the cord are connected through to the plug, and a ringing circuit is established over which ringing current from the generator GEN is projected intermittently to signal the called subscriber. In addition to the functions described, relay 209 also closes a circuit for relay 207 at its armature 228. Upon energizing, relay 207 opens the circuit of the call signal lamp L⁴ at armature 222, and at armature 221 closes a circuit for relay 201, which includes the grounded conductor 235. Upon energizing, relay 201 establishes a locking circuit for itself at its armature 213, and at the back contact of the same armature disconnects ground from the holding conductor 234. The last operation above mentioned, brings about the release of the line switch C' and the register set upon which the called number was registered, which will now be explained. When ground is disconnected from conductor 234, the holding circuit for hold winding of line switch C' and relay 306 is broken and the plunger of the line switch C' and the relay 306 are restored to normal. When relay 306 deenergizes at armature 321 it closes a circuit for the release magnet 325 of switch P, and at armature 319 removes ground from the holding circuits of relay 304, 305, 400 and 405. The circuit of the release magnet of the timing switch P, is broken when its wiper 330 moves off its contact bank. The register set is now completely restored to normal in readiness for use in registering another telephone number.

When ground is disconnected from conductor 284 lamp L' is extinguished, and in case there is no other call waiting at this time relay 262 of the consecution control switch CCS will be deenergized. If a call is waiting, however, relay 262 will be held up in series with one of the other lamps shown, such as lamp L² or lamp L³ for example, and when relay 260 falls back, the line relay 261 will again be energized. Since the first test contact in the bank traversed by wiper 264 has just been grounded by the deenergization of relay 305, the operation of the line relay 261 causes the consecution control switch CCS to advance its wipers into engagement with the test contact which is associated with the first register set upon which a registered call is waiting, and this call is then switched on to the lamps of the indicating device, the same as has been described.

Returning now to the cord circuit O, it has been explained how the connection has been completed to the line of the called substation A', and ringing current is projected 5 out over the called line to signal the subscriber. During the ringing operation a tone is induced in the left hand winding of the repeating coil of the cord circuit O, by reason of the fact that the ringing circuit 10 includes the upper right-hand winding of the repeating coil, and this tone is audible to the calling subscriber, who is thus advised that the signalling operation is proceeding satisfactorily. The ring cut-off relay 208 is included in the ringing circuit and when the called subscriber answers, this relay pulls up and locks itself in energized position by attracting its armature 225, which operation includes the upper winding 15 of the ring cut-off relay in the circuit of the sleeve relay 209. Relay 208 also breaks the ringing circuit at armature 226, and at the working contact of the same armature finally completes the talking circuit. The 20 transmitter at the called station is now supplied with talking current through the right-hand windings of the repeating coil and through the upper and lower windings of the battery feed relay 206. Relay 206 energizes 25 in the first instance through its lower winding alone, since the upper winding is normally short circuited in order to keep it out of the ringing circuit, but when the relay pulls up both its windings 30 are included in the battery feed circuit. In energized position, relay 206 closes a circuit for the reversing relay 205. Upon energizing relay 205 reverses the trunk conductors 130 and 131 as regards their connections with the windings of the line relay 204, 35 and the direction of current flow in the calling line is thus reversed. The direction of current flow through the upper winding of the electro-polarized relay 105 at repeater E is therefore reversed and this relay is now 40 operated. At armature 118, relay 105 places a shunt around armature 116 and its resting contact and at armature 119 completes a circuit for reversing relay 100. The operation 45 of relay 100 reverses the direction of current flow in the calling line. This operation may be used for operating a meter, or for other similar purposes, and is provided in accordance with standard practice although it is 50 of no utility in the particular system shown herein.

The required connection having been established, the subscribers may now converse as desired. When the conversation is finished both subscribers will hang up their receivers, and the replacement of the receiver at the calling station A causes the automatic switches to be restored to normal. When the receiver is replaced the circuit of the 55 line relay 204 is broken, resulting in the de-

energization of this relay and also in the deenergization of the slow-acting relay 203. Relay 203, on deenergizing, closes a circuit for the supervisory lamp L⁵ at armature 217. 70

When the operator observes the lighted supervisory lamp L⁵ she will remove the plug of the cord circuit O from the jack and relays 209, 208, and 207 are deenergized and restored to normal. By the falling back of 75 relay 207 the circuit of the supervisory lamp L⁵ is broken at armature 223. All the apparatus has now been restored and is ready for use in handling another call.

In case the operator should accidentally 80 withdraw the plug from the jack before the automatic subscriber has hung up his receiver, means is provided for flashing the lamp L⁴ to call her attention to the error. When the plug is withdrawn relays 209 and 85 207 are deenergized, and since relay 201 is now in energized position, the calling subscriber not having yet hung up his receiver, a circuit is completed for the lamp L⁴ which includes the interrupter I, and the lamp will 90 be flashed to attract the attention of the operator. If the operator remembers the jack from which the plug was withdrawn she can re-plug immediately, otherwise she will 95 plug into a special jack (not shown) which connects with her head set so that she can talk to the calling party and ask him what number he was disconnected from.

Certain details of the system will now be explained which it was not convenient to go 100 into before, and the first thing which will be considered is the function of the timing switch P, Fig. 3. This switch is provided for the purpose of handling the so-called "mutilated calls," which are calls arriving at 105 a register set and which, because of improper dialling by the calling subscriber, or failure of some switch to function properly, are not completely registered. It will be understood that in the ordinary operation of the 110 system a call is displayed to the operator by the energization of relay 305 followed by the energization of relay 304 at the proper time, under the control of the consecution control switch CCS. The energization of relay 305, 115 however is contingent on two series of impulses being transmitted to the register control switch RCS, which causes the switching relay 405 of the register set R² to be energized to ground conductor 414; and it will 120 be appreciated, therefore, that if less than two digits are registered, relay 305 will not ordinarily be energized, and the partially registered number will never be displayed to the operator. Experience has shown that 125 these incomplete calls are a fruitful source of trouble, since each such call occupies a register set until the calling subscriber hangs up his receiver, without giving the operator a signal of any kind. In order to eliminate 130

- the difficulty pointed out, the timing switch P is provided and this switch is adapted to bring about the display of any call after a certain definite time interval, regardless of 5 whether all of the digits in the called number are registered or not. The operation is as follows: Assuming that a call has arrived at the register set shown in Figs. 3 and 4, when relay 306 pulls up a circuit is closed 10 for the stepping magnet 324 of timing switch P at armature 320, and the timing switch begins to operate under the control of the time control impulse sender, indicated by the reference character T. This impulse sending mechanism is so arranged that the conductor 322 is grounded, at one second intervals with the result that after the expiration of ten seconds the wiper 331 closes a circuit by which ground is connected with conductor 414. This causes relay 305 to be energized, and whatever digits have been registered in the meantime are displayed to the operator in due course. It will be obvious 15 that the time interval can be varied as desired, but the interval of ten seconds herein mentioned is believed to be about right, since it has been determined by observing a large number of calls that this time interval is long enough to allow ordinary calls to be 20 completely registered in practically all cases. Of course, if the subscriber is very slow in calling a number the time interval will have elapsed before he is through, but this causes no particular harm, since the circuit arrangement is such that the subsequent registration of the digits is not interfered with. It is intended that the "mutilated" calls will 25 be extended by the operator to a complaint or trouble operator by plugging into trunk lines provided for this purpose in order that the regular operator may be free to confine 30 her attention to handling the regular traffic.
- A novel feature, consisting of an arrangement for making all trunks busy leading 35 from an operator's position, either when the operator leaves her position, or when all call register sets are in use, will now be described.
- Referring to relay 108 of Fig. 1, it may 40 be pointed out that this a gang relay, and when operated extends ground over conductors such as 133 to each repeater of the particular group to which it is common. Relay 108 is operated over conductor 109 leading 45 to the manual exchange, there being one of these conductors for each group of trunk lines. Conductor 109 may be grounded at two different points to cause the operation 50 of relay 108. First, assuming that the operator desires to leave her position, she will withdraw her plug 236 from jack 237, permitting relay 238 to be deenergized, which closes a circuit from ground, armature 250, conductor 109, and relay 108 to battery. 55 Relay 108 energizes and, assuming that the
- trunk line associated with the repeater E is idle, closes a circuit from ground, armature 132 and its working contact, conductor 133, armature 134, armature 117, and conductor 77 to test contact 74. A similar circuit is 60 completed by armatures 132' and 132'' to the test contacts of all other idle trunks of the group leading to this particular operator's position of the manual exchange.
- Attention is called to the fact that if the 65 trunk line associated with repeater E is in use at this time it will not be effected by the operation of relay 108 as the busying circuit will be interrupted either at armature 134 or 117, but as soon as the trunk becomes 70 idle, armature 134 and 117 will have returned to normal and the trunk line will be again made busy, providing the gang relay 108 is still energized.
- The other condition under which relay 75 108 is operated is when all the register sets assigned to the position are busy.
- Referring to the relay 327 of Fig. 3, this relay is normally short circuited by a common conductor having branches such as 340 80 leading to the back contact of armature 319 of relay 306 to ground. It will be seen, therefore, that the relay 327 will operate only when the relays 306 of all register control switches are energized, or in other 85 words, when all the register sets are in use. Assuming this to be the case, relay 327 energizes and grounds conductor 109, thus causing relay 108 to operate and function 90 in the same manner as hereinbefore described.
- Having described my invention, what I consider new and desire to have protected by Letters Patent will be pointed out in the 95 appended claims.
- What I claim as my invention is:
1. In a telephone system, a manual exchange, trunk lines terminating in cord circuits in said exchange, automatic substations having access to said trunk lines for calling the subscribers in the manual exchange, a plurality of relay register sets for registering the telephone numbers of called manual stations, and an automatic switch for each of said cord circuits for connecting 105 its associated cord circuit with an idle register set when the cord circuit is taken for use, and means for preselecting idle register sets ahead of the calls.
  2. In a telephone system, a manual exchange, trunk lines terminating in cord circuits in said exchange, automatic substations having access to said trunk lines for calling the subscribers in the manual exchange, a 110 plurality of register sets for registering the telephone numbers of called manual stations, an automatic switch for each of said cord circuits for connecting its associated cord circuit with an idle preselected register set when the cord circuit is taken for use, and 115

means for pre-selecting idle register sets ahead of the calls.

3. In a telephone system, a manual exchange, trunk lines terminating in cord circuits in said exchange, automatic substations having access to said trunk lines for calling the subscribers in the manual exchange, a plurality of relay register sets for registering the telephone numbers of called 10 manual stations, an automatic switch for each of said cord circuits for connecting its associated cord circuit with an idle pre-selected register set when the cord circuit is taken for use, and means for pre-selecting 15 idle register sets ahead of the calls.

4. In a telephone system, a manual exchange and an automatic exchange, a trunk line accessible to automatic switches in the automatic exchange and terminating in a 20 cord circuit in the manual exchange, a register set comprising a series of relay groups for registering the numbers of manual lines called over said trunk line, a switch individual to said cord circuit for extending a connection to the said register set when a line is being called, a register control switch, and a relay in said cord circuit for repeatedly operating said control switch to successively control the setting of said relay 25 groups.

5. In a telephone system, a manual exchange, an automatic exchange, a trunk line in said automatic exchange terminating in a 30 cord circuit at said manual exchange, call register sets comprising relay groups, a line switch associated with said cord circuit, a master-switch for pre-selecting an idle register set, and means responsive to the seizure 35 of said cord circuit for causing said line switch to seize the pre-selected register set.

6. In a telephone system, an automatic exchange, a manual exchange, trunk lines extending from said automatic to said manual exchange, call register sets in said manual 40 exchange accessible to said trunk lines, a relay in said automatic exchange common to said trunk lines, a conductor extending from the automatic to the manual exchange, and means at the manual exchange operated when 45 all the register sets are in use for causing the energization of said relay over said conductor to make all of said trunk lines busy.

7. In a telephone system, two conductor 50 trunk lines extending from an automatic to a manual exchange, a relay at the automatic exchange for making all of said trunk lines busy when energized, and means at the manual exchange operable automatically to cause the energization of said relay, said 55 means including a second relay common to said trunk lines.

8. In a telephone system, an automatic exchange, and a manual exchange, trunk lines comprising only two conductors extending 60 from said automatic to said manual ex-

change, a single conductor extending from said automatic exchange to said manual exchange common to said trunk lines, means controlled thereover for making all the trunks which are idle artificially busy and 70 for making all of the busy trunks artificially busy as soon as they become idle.

9. In a register set, a plurality of groups of permutational relays, an automatic switch, means for operating and releasing 75 said switch a plurality of times in accordance with a plurality of digits in a called number, and means including a wiper in said switch for controlling the setting of said relay groups successively. 80

10. In a register set, a plurality of groups of permutational relays, an automatic switch, means for operating and releasing 85 said switch a plurality of times in accordance with a plurality of digits in a called number, means including a wiper in said switch for controlling the setting of said relay groups successively, and a set of digit indicators controlled by said relay groups for displaying the called number. 90

11. In a register set, a plurality of groups of permutational relays, an automatic switch, means for operating and releasing 95 said switch a plurality of times in accordance with a plurality of digits in a called number, means including a wiper in said switch for controlling the setting of said relay groups successively, a group of lamps associated with each relay group, and contacts controlled by actuated relays in said 100 groups for lighting a particular lamp in each group to display the called number.

12. In a register set, a series of digit lamps, permutational relays less in number than said lamps operable singly and in combination to light any desired lamp, and an automatic switch controlled by a calling subscriber in accordance with a digit in a called 105 number to selectively operate said relays as set forth. 110

13. In a telephone system, an automatic exchange, a manual exchange, trunk lines extending from said automatic exchange to said manual exchange, call register sets in said manual exchange accessible to said trunk 115 lines, a normally deenergized relay in said automatic exchange common to said trunk lines, a conductor extending from the automatic exchange to the manual exchange, means at the manual exchange operated when all the register sets are in use for causing the operation of said relay over said conductor, and means controlled by said relay for making all of said trunk lines busy. 120

14. In a telephone system, trunk lines extending from an automatic to a manual exchange, automatic switches having access to said trunk lines, a relay at the automatic exchange having a set of contacts for each 125 trunk line effective when said relay is oper- 130

- ated to make said trunks busy to said automatic switches, and means including a conductor common to said trunk lines for automatically causing the operation of said relay. 45
15. In a telephone system, trunk lines extending between an automatic and a manual exchange, a relay at the automatic exchange having a set of contacts for each trunk line, effective when said relay is energized, to make said trunk lines busy, and means at the manual exchange operable automatically to cause the energization of said relay. 50
16. In a register set, a plurality of groups of permutational relays, an automatic switch having access to conductors extending to relays of one of said groups, means for operating said switch in accordance with a digit in a called number, means for completing circuits for one or more of the permutational relays of the connected group following the operation of said switch, and means controlled over said circuits for releasing said switch and for transferring the conductors accessible to said switch to relays of a second one of said groups, said first means being then effective for reoperating said switch in accordance with a second digit of a called number for closing energizing circuits for one or more relays of said second group. 55
17. In a register set, a plurality of groups of relays, a switch responsive to successive series of impulses, circuits selected by said switch each time it is operated to energize a particular permutation of one or more relays, and means operated after each series of impulses for causing the circuits selected by the next series to include relays of the next group. 60
18. In a register set, a series of ten digit lamps, four relays operable singly and in combination to light any desired lamp, and an automatic switch variably controlled by a calling subscriber in accordance with a digit in a called number to selectively operate said relays as set forth. 65
19. In a register set, ten lamps all connected to the same pole of a source of current, ten conductors terminating in said lamps, respectively, a plurality of relays less in number than the number of said conductors operable singly and in combination for selecting any of said conductors, and means for selectively operating said relays as set forth. 70
20. In a telephone system, trunk lines each comprising only two conductors extending from an automatic exchange to a manual exchange, a conductor common to said trunk lines, a relay at the automatic exchange for making all said trunks busy when energized, a second relay at said manual exchange common to said trunk lines, and contacts on said second relay adapted when closed to close a circuit over said common conductor to energize said first relay. 75
21. In a telephone system, a manual exchange, an automatic exchange, a trunk line in said automatic exchange extending to and terminating in said manual exchange, call register sets comprising relay groups in said manual exchange, a lineswitch in said manual exchange associated with said trunk line, a master switch for preselecting an idle register set, and means responsive to the seizure of said trunk line at said automatic exchange for causing said lineswitch in the manual exchange to seize the pre-selected register set. 80

In witness whereof, I hereunto subscribe my name this 6th day of May, A. D., 1922.

BERNARD D. WILLIS.
